UNITED STATES PATENT OFFICE.

HAROLD B. CRANSHAW, OF BOSTON, MASSACHUSETTS.

RECEPTACLE.

1,367,356.

Specification of Letters Patent.

Patented Feb. 1, 1921.

Continuation in part of application Serial No. 12,646, filed March 6, 1915. This application filed February 23, 1918. Serial No. 218,660.

To all whom it may concern:

Be it known that I, HAROLD B. CRANSHAW, a citizen of the United States of America, and resident of Boston, in the county of Suffolk and State of Massachusetts, have invented new and useful Improvements in Receptacles, of which the following is a specification.

This invention relates to paper receptacles and more particularly to sputum cups of the type intended to be destroyed after use.

In articles of this character it is essential that the receptacles be covered and considerable difficulty has been experienced in producing a satisfactory covering. It is the object of the present invention to provide a covered receptacle of the character referred to having a pivotal cover which can be readily hinged to the cup, which may be hinged to the cover with or without the use of metallic or other auxiliary attaching means, which will not become detached from the cup under ordinary conditions of usage even when employing no auxiliary attachment means, and to provide a covered receptacle which may be formed of two parts, one part being adapted to form the cup and the other part the cover, and each part being adapted to be formed by a single stamping operation.

The preferred embodiments of my invention are illustrated in the accompanying drawings, in which—

Figure 1 is a side elevation of the receptacle showing the cover slightly raised;

Fig. 2 is a rear elevation of the receptacle;

Fig. 3 is a plan of the blank from which the cup is formed;

Fig. 4 is a plan view of the receptacle showing one form of metallic auxiliary fastener; and

Fig. 5 is a side elevation of Fig. 4.

The embodiments of my invention illustrated in the drawings each comprises a cup C and a cover C', the cup C having a tab T projecting through a slot S in the cover C'. The cup C is preferably formed from a blank such as shown in Fig. 3, the blank being folded along the dash lines to form the cup in a manner which will be readily understood. The portion 1 constitutes the bottom of the box, 2 the rear side, 4 the left side, 6 the front side, 8 the right side; the portions 3 and 9 are folded inwardly along

the inside of the rear side 2; the portions 5 and 7 are folded inwardly along the inside of the forward side 6; and the projections 10, 11, 12 and 13 are folded inwardly and interlocked together as shown.

The portions 10, 11, 12 and 13 when thus folded and interlocked, form a continuous flange which serves to prevent the escape of the contents of the cup, should the latter be accidentally turned on its side or completely over-turned.

The cover C' consists of a flat sheet of material and preferably extends somewhat over the edges of the cup. Both the cup and the cover are preferably composed of stiff paper, the cover being somewhat more inflexible than the cup so as not easily to become warped or distorted.

In my improved means for pivotally attaching the cover to the cup the tab is preferably formed on the cup and the slot in the cover and the tab is preferably formed as an integral part of the cup. As illustrated in Fig. 3 the tab is struck-up from the portion 10 of the cup blank with its base extending along the line 14 which constitutes the upper edge of the rear side of the box when the blank is folded. Thus the top normally extends from the edge of the cup in alignment with the rear side 2 as shown in Figs. 1 and 5. However, the tab is sufficiently flexible to permit its being bent backwardly when the cover C is raised.

A characteristic feature of my invention is that the tab T is wider at its top than at its base and that the slot S is narrower than the top of the tab, and these relative dimensions are preferably secured by forming the tab in the shape of a keystone as shown most clearly in Fig. 3. In the embodiments illustrated the width of the slot in the cover is substantially equal to or slightly greater than the width of the tab at its base so that the cover fits snugly around the tab and this is the preferred construction.

In inserting the tab through the slot the tab is flexed into such form that it is no wider than the slot, as for example by squeezing inwardly on the opposite ends of the tab, and in order to facilitate the insertion the cover may also be flexed on one or both sides of the slot so as to widen the slot and provide a larger opening for the flexed tab. After the tab is inserted through the slot the tab is permitted to straighten out

and when the slot is of substantially the same width as the base of the tab the cover is held close to the cup. Moreover, there is no tendency for the cover to pull off the tab unless the tab is flexed in some such manner as above referred to.

While the above described construction is wholly satisfactory for most purposes an auxiliary fastening means is desirable under certain severe conditions of usage. I therefore provide a clip characterized in that it fits over the edge of the cover and extends through the tab either above or below the cover or on both sides of the cover. In Figs. 4 and 5 I have illustrated an embodiment of auxiliary fastening means comprising a bent wire clip K resembling an ordinary paper clip. The clip K comprises a long loop k extending from the rear edge of the cover, along the upper side of the cover, and thence through an opening in the tab, and a shorter loop k' extending from the rear edge of the cover, along the under side of the cover, and thence through an opening in the tab immediately below the cover. The clip K is placed in position merely by sliding it over the rear edges of the cover, after the tab has been inserted in the cover slot, with the loops k and k' disposed on opposite sides of the cover.

What I claim is:

1. A receptacle comprising a body member, a cover member, one of said members having a slot, and a tab on the other member projecting through said slot to pivotally connect the two members together, said tab tapering inwardly and said slot having a width less than the maximum width of the tab.
- 40 2. A receptacle comprising a cup, downwardly and inwardly inclined interlocking extensions of the upper edges of the side walls of the cup, forming a continuous flange for preventing the escape of the contents of the cup, a cover for the cup, and a tab on the cup projecting through a slot in the cover, the tab having a keystone shape and the slot having a width less than the maximum width of the tab, together with auxiliary fastening means for the said cover comprising a locking member inserted through an opening in the tab and extending along the said cover, thereby locking the cover securely in position.

3. A receptacle comprising a body member, a cover member for the body member, one of said members having a slot therein, a tab extending from the other member through said slot, and a clip fitting over the edge of said slotted member and extending through the tab on at least one side of the slotted member.

4. A receptacle comprising a body member, a cover member for the body member, one of said members having a slot therein, a tab extending from the other member through said slot, and a clip fitting over the edge of said slotted member and extending through the tab on both sides of the slotted member.

5. A receptacle comprising a cup, a sheet cover for the cup, a keystone shaped tab projecting from the cup through a slot in the cover, and auxiliary fastening means for the said cover comprising a clip fitting over the edge of the cover and extending through an opening in the tab on at least one side of the cover.

6. A receptacle comprising a cup, a sheet cover for the cup, a tab projecting from the cup through a slot in the cover, and auxiliary fastening means for the said cover comprising a clip fitting over the edge of the cover and extending through an opening in the tab on both sides of the cover.

7. A receptacle comprising a cup, a sheet cover for the cup, a tab projecting from the cup through a slot in the cover, and auxiliary fastening means for the said cover comprising a clip fitting over the edge of the cover and extending through an opening in the tab.

8. A receptacle comprising a cup, downwardly and inwardly inclined extensions of the upper edges of the side walls of the cup, two of said extensions, on opposite sides of said cup being provided with notches on their lower free edges, and the extensions of the remaining sides of the cup being provided on their lower free edges with wedge shaped projections, coöperating with the said notches, whereby the said extensions are interlocked, to form a continuous flange for preventing the escape of the contents of the cup.

Signed by me at Boston, Massachusetts, this 29th day of January, 1918.

HAROLD B. CRANSHAW.
